UNITED STATES PATENT OFFICE

Patent No. 1,988,682 issued Jan. 22, 1935, to Nicholas Dicker, New York, N. Y., for a fur pointing machine.

Application filed August 17, 1931, Serial No. 557,611.

7 Claims. (Cl. 149—24)

The present invention relates to a fur pointing machine for the ornamentation of fur.

It is a customary practice in the fur processing art to "point" or glue light colored hairs in a fur skin. The said "pointing" has been done manually for a long number of years. My fur pointing machine does away with the manual labor and performs this kind of work automatically by machine.

An object of my invention, which is the result of several years of experimental investigation of the subject is to render automatic the feeding, picking, conveying and gluing of hair of a badger at successive spots on a fur-skin.

Another object of my invention is to provide automatically controlled air blowing means to cause a regulated blast of air to be directed onto the fur-skin for separating the hair and forming a clear exposed spot on the fur-skin, and to provide automatically operating mechanism for picking one or more hairs, cutting said hair to a desired length, gluing one end of said piece and "pointing" or setting said glued-end downward in successive spots as selected by the operator.

Another object of my invention resides in the particular arrangement and structural features of the cooperating mechanism.

With the above and other objects in view the invention will be hereinafter more particularly described, and the combination and arrangement of parts will be shown in the accompanying drawings and pointed out in the claims which form part of this specification, it being understood that the embodiment herewith shown is merely illustrative and that various changes in the form, proportion, size and minor details of construction within the scope of the claims may be resorted to without departing from the spirit of the invention.

Reference will now be had to the drawings, wherein like numerals of reference designate corresponding parts throughout the several views, in which:

Fig. 1 is a side elevation of my fur pointing machine.

Fig. 2 is a perspective elevation of the operating end of the machine.

Fig. 3 is a perspective side elevation of the interior of the machine.

Fig. 4 is a section of the hair feeding magazine taken as on line 4—4 in Fig. 1.

Fig. 5 is a view of the mechanism on the line 5—5 in Fig. 1 set for guiding the conveying device toward the picking device.

Fig. 6 is a view of mechanism in Fig. 5 set for

guiding the conveying device toward the pointing rod.

Fig. 7 shows a fragmentary plan view of the shear mechanism.

Fig. 8 is a plan view of the conveyor gripping means.

Figure 9 is a bottom view of the fur pointing machine.

Figure 10 is a section taken through the pointing rod and gripping device as seen from the front of the machine in Fig. 2.

Figure 11 is a rear elevation of the ratchet wheel and pawl mechanism shown in perspective in Figure 3.

Figure 12 is a cross-sectional view of the shears, the section being taken as on line 12—12, in Figure 7.

Figure 13 is an enlarged top view of the picking device when in elevated position as seen in Fig. 2, including air suction means, but without top cover.

Figure 14 is a sectional view of the picking device, the section being taken as on line 14—14, in Fig. 13.

In the illustrated embodiment of the invention, Fig. 1 shows a fur pointing machine 10, a drum 11, mounted for rotary and sliding motion on a shaft 12, disposed within bearings 155, 155, fastened to the base plate 153. Suitably supported in a frame 156, fastened to the base plate the fur pointing machine 10, is a power shaft 13, on which is mounted a cam 14. Adjacent the cam 14 is the operating lever 15 of an air valve 16, having an air supply 157, a frame 158, fastened to the base-plate 153, and spring means therein (not shown) which forces the valve stem against the air port and keeps the valve normally closed. The lever 15 mounted on the air valve 16 has one end in engagement with the frame 158, of the air valve 16, and the other end is positioned near and comes in contact with the cam 14, and the said lever is operated by the cam once every revolution of the power shaft 13. The air valve 16 is thus opened once every revolution and causes a blast of air to be transmitted through an air pipe 17 pointing upon a spot on the drum 11.

A fur-skin 18, to be improved by "pointing" with hairs from a badger is laid upon the drum 11 and assumes the contour of the drum. The air from the air pipe 17, causes a jet of air under pressure to spread apart the hairs on the fur skin 18, and to form a clear spot 19, exposing a portion of the fur-skin, as best shown in Figure 2. In this position of the fur-skin,

my pointing machine 10 causes one or more hairs of a badger fur to be glued on the cleared spot 19, by means of mechanism to be described.

As just mentioned, the drum 11, is mounted
5 for rotary and sliding motion on the shaft 12,
and when one or more hairs have been glued
on the clear spot 19, the operator may either
rotate or slide the drum 11, on the shaft 12,
and thus shift the fur-skin so that another por-
10 tion thereof is exposed to the action of the jet
of air. The jet of air spreads apart the hairs
on the said portion of the fur-skin and the op-
erator causes the said mechanism to glue one or
more hairs of a badger on the last mentioned
15 portion of the fur-skin. In this way, the op-
erator repeatedly shifts the fur-skin and causes
one or more hairs to be glued at any number
of positions on the fur-skin.

My pointing machine 10 comprises a feeding magazine 20 for the supply of loose hairs, a picking device 21, shears 22, a conveying device 23, a pointing rod 24, and a gluing device 25, cooperatively associated.

The feeding magazine 20, comprises a U-shaped member 26, open at the top and having a spring pressed sliding plate 27, and cross bars 28, 29 (see Fig. 2), facing the operating end 31, of the pointing machine 10. A quantity of hairs 32, from a badger may thus be placed in an upright position in the U-shaped member 26 and pressed lightly toward the operating end 31 by means of the spring 33. A threaded member 34 (see Fig. 4) serves to regulate the tension of the spring 33 against the plate 27 and against the hairs 32. As best shown in Figure 4, the U-shaped member 26 is housed in a frame 35 which is adapted to reciprocate horizontally between side walls 36, 36, positioned at the operating end of the fur pointing machine 10. This horizontal reciprocating motion is imparted to the member 26 by means of a ratchet-wheel 37 (see Figs. 3 and 11) and a link 38, attached thereto and having its free end suitably attached to the frame 35. The hair feeding magazine 20 (see Fig. 1) is also adapted for vertical adjustment by means of a spring 151, under the foot paddle 39. The foot paddle 39 is connected by means of levers 30 and 40 to a lug 41, depending from the U-shaped member 26; the lever 30 being fixed to the pointing machine frame 42, at a point 43 at the rear of the frame 42. The operator may press down the foot paddle 39, and thus lower the hair feeding magazine 20, or he may raise his foot and permit the spring 151, to raise the foot paddle 39, and the hair feeding magazine 20. The vertical adjustment may also be accomplished by hand.

As shown in Figure 2, the hair picking device 21 is integral with a cylindrical arm 44, attached to a horizontal shaft 45, and swung around thereby, and can swing upwardly to meet the hair feeding magazine 20, and can also swing downwardly to meet the shears 22.

65 A bevel gear 46 is mounted on the arm 44 and is adapted to mesh with a bevel gear 47 fixed to the housing 48, for the shaft 45. The bevel gears 46, 47 impart a rotary motion to the picking device 21, about the arm 44. The picking device 21 is thus adapted to both rotate and swing simultaneously so that when the shaft 45 rotates and swings the picking device upwardly to meet the hair magazine 20, the 70 picking device faces the hairs 32 and when the 75

picking device swings downwardly to meet the shears 22, it faces the shears.

As shown in Figure 7, the shears 22 comprises two blades 49 and 50, the blade 49 being positioned on top, and pivoted to blade 50 by means of a pivot pin 51. An arm 52 integral with the shear blade 50 is held in a stationary position fastened to a stationary cam plate 53, shown in Fig. 1. A sliding arm 54, is adapted to reciprocate within an enclosure 55, integral with the shear member 50. The arm 54, is provided with an angular extension 56, having a slot 57, which is in engagement with a pin 58, in an angular extension 59, of the shear member 49. It will thus be noted that when the sliding arm 54, is caused to reciprocate, a pivotal or shearing motion is imparted to the shear blade 49, in relation to the stationary blade 50.

As best shown in Fig. 9, the conveying device 23, comprises an elongated bar 60, mounted to slide in a frame 61, and in housing 152, integral with the cam plate 53. The bar 60, passes through the housing 152, and extends to the operating end 31. The frame 61 is adapted to swing about a shaft 62, at the lower end of which there is fixedly mounted a crank arm 63. The arm 63, is connected to and is adapted to reciprocate a connecting rod 64, in engagement with a pin 65, fixed to the said bar 60. At the free end of the bar 60, best shown in Fig. 8, there has been provided hair gripping means 66, consisting of a stationary jaw 67, and a spring pressed pivoted jaw 68, which is swung to an open or closed position by means of a rod 69, affixed thereto. The said pivoted jaw 68, shown in a closed position in Figure 8, and is held in said position by means of a spring 70. Intermediate the gripping end 66 of the conveying device and the pin 65, there has been provided a pin 71, fixed in right-angular relation with the bar 60, and which is adapted to engage with a diagonal slot 72, in the cam plate 53, shown in Fig. 5, so as to cause the hair gripping means 66, on the bar 60, of the conveying device 23, to communicate with the hair picking device 21, when the said picking device is in its downward position adjacent the shears 22, and to grip the hair from the picking device 21. A longitudinally positioned slot 73 of the same dimensions as the slot 72 has been provided in the cam plate 53, so as to join and form an angle with the slot 72. At the junction of the slots there has been provided an oscillating adaptor 74, having therein a slot-end 75 of the same dimensions as the slots 72 and 73. When the conveying device 23 is to be moved away from the picking device, the intermediate pin 71 is caused to move along the diagonal slot 72 till it reaches the slot-end 75 in the adaptor 74, when the said adaptor is caused to oscillate toward the slot 73 and form a continuation of said slot as shown in Fig. 6. The pin 71 is then constrained to follow the slot 73 and to move along with the conveying device 23, comprising the bar 60, and the gripping means 66, toward the front end of the machine when the gripping means 66 carries the hairs 32 past a perforated plate 76, having a layer of glue thereon from the glue device 25, and causes the lower ends of the hairs 32 to be covered with glue. The gripping means 66 with the glued hairs 32 then continues the longitudinal motion along the slot 73 till the gripping means 66 communicates with a hair gripping device 77, at the lower end of the pointing rod 24.

The gluing device 25 comprises a glue container 78, fastened to the base-plate 153, by means of an arm 154, shown in Figure 1, and is open at the top. The perforated plate 76 is positioned in a horizontal plane and is mounted for vertical reciprocation by means of an integral bar 80, which is housed in a frame 81, fastened to the main frame 42.

The pointing rod 24 is slidably mounted in a pair of lugs 82, 82, and is adapted for reciprocation by means of a link 83 connected to a disk 84, mounted on the main shaft 85. The hair gripping device 77 comprises a stationary jaw 159, and a spring pressed movable jaw 160, pivotally mounted on a pin 164, and pressed against the jaw 159, by a spring 165, the movable jaw being swung to an open position by raising an arm 88, slidably housed in a slot 166, in the pointing rod 24, as best shown in Figure 10. Lowering the arm 88 causes the said gripping device jaws to close and grip the hairs 32 from the hair gripping means 66, on the conveying device 23.

Slidably mounted in a pair of caps 89, 89, is a control arm 90, having adjustably secured thereto two spaced stop pins 91, 91, which serve to raise and lower the arm 88, and thus to open and close the hair gripping device 77. Vertical reciprocating motion is imparted to the control arm 90, by means of a crank pin 92, fastened to a crank arm 161, mounted on a shaft 93, and rotated by a gear 94, shown in Fig. 3, the said crank arm 92 being in engagement with a bifurcated extension 95, on the control arm 90. The control arm is also provided with an angular extension 96, and an integral upright member 162, having a pawl 97, attached thereto. The said pawl is held in contact with the wheel 37, by a spring 163, shown in Figure 11. The up and down motion of the control arm 90, causes the pawl 97 to impart a rotary motion in one direction to the ratchet wheel 37.

The main shaft 85 is driven from the power shaft 13, shown in Fig. 1, in any suitable manner such as by means of a chain 98, and has mounted thereon a worm gear 99, which meshes with a worm gear 100, mounted to drive a shaft 101. As best shown in Fig. 1, a crank arm 102 is fastened to the shaft 101, and engages with a rack 103, by means of a pin 104. The rack 103, is in mesh with a gear 105, fastened to the shaft 45 shown in Fig. 2, and when the shaft 101 rotates, the rack 103 reciprocates and causes the gear 105, the shaft 45, and the hair picking device 21, to swing up and down through an arc of about 180°.

Adjacent the worm gear drive on the shaft 85, are three cams 108, 109 and 110. Cam 108 operates in an aperture 111 in a slide 112 and causes said slide to reciprocate up and down in relation to the pointing machine frame 42, as shown in Fig. 1. The slide 112 is provided with a slot 113 at its lower end in which is a pin 114, forming an integral part of a lever 115, which is pivoted at 116. A link 117 is connected to the lever 115, at its upper end, and is connected to an angular lever 118 pivoted at 119 at its lower end. A link 120 connects the lever 118 to the sliding arm 54 and completes the series of levers, causing the slide 112 to reciprocate the arm 54. At the free end of the arm 54, there has been provided an

extension 121, which serves the purpose of operating a lever 122 on the picking device 21, so as to open the hair gripping jaws on the gripping device 21, and permit the gripping means 66 of the conveying device 23 to grip the sheared hairs 32 from the gripping device 21.

As best shown in Figures 13, and 14, the lever 122, is pivotally mounted on a pin 167. A triangular recess 168, has been provided at the central portion of the lever 122, the recess being designed to receive the end portion 169, of a jaw carrying member 170, pivotally mounted on a screw 171. The jaw 172, being integral with the member 170. A movable jaw 173, has been pivotally mounted on a pin 174. A cover 175, shown in Figure 14, has been provided at the upper portion of the picker 21, and a spring 176, in engagement with the screw 171, serves to press the jaw carrying member against the lower face of a frame 177. A pin 178, is slidably housed in an aperture in the jaw 172, and abuts against the jaw 173. In the position shown in Figure 13, the jaws 172, and 173, are closed. A leaf spring 179, has been fastened to the cylindrical arm 44, and extends into the frame 177, and engages with a connecting member 180, which enters into notches in the spring 179, and in the lever 122. It will thus be noted that when the lever 122, is swung to the left of that shown in Figure 13, that the jaw carrying member 170, will be swung on the screw 171, and that when the pin 178, contacts with the side wall 181, of the frame 177, the jaw 172, moves a distance slightly larger than that moved by the jaw 173, and that a minute opening appears between said jaws.

The cam 109 operates in an aperture 123 in a slide 124. At the lower end of the slide 124, there has been provided a rack 125, which meshes with a gear 126, mounted on a shaft 127. A crank arm 128, shown in Fig. 1, is fixed to the shaft 127, and engages with a link 129, which is in engagement with a link 130, having a pivoted end 131. A link 132 is pivoted at one end at 133 to the link 130 and is attached at the other end to a rack 134. The rack 134 is in mesh with a gear 135 mounted on a shaft 136. The shaft 136 extends downwardly into the cam plate 53, and has a gear 137 mounted at its lower end, as shown in Fig. 5. A rack 138 has one end in mesh with the gear 137 and is in mesh at its other end with the rotatable adaptor 74, which is provided at a portion of its circumference with gear teeth 139. It will thus be seen that the cam 109 causes the adaptor 74 in the cam plate 53 to oscillate.

As best shown in Fig. 3, the cam 110 operates in an aperture 140, in a slide 141. At the lower end of the slide 141, there has been provided a rack 142, which meshes with the gear 94, mounted on the shaft 93. It will thus be seen that the cam 110 operates the shaft 93, the crank arm 161, and the crank pin 92 and causes the up and down motion of the control arm 90, the integral upright member 162, and the pawl 97.

As shown in Figure 2, an angular lever 148, is mounted in an upright position on a pivot 182, the upper end of the lever being positioned under the bifurcated extension 95, of the control arm 90, and when the control arm moves downward, the extension 95, contacts with the lever 148, and causes its lower end to swing towards the conveying device 23, and to strike the rod 69, and opens the jaws of the hair gripping means 66, of the conveying device 23.

Mounted on the shaft 93 is a crank 143, which engages with the angular extension 144, on the bar 80, carrying the perforated plate 76, of the gluing device 25. The downward swing of the 5 crank 143 causes the perforated plate 76 to be lowered into the glue container 78, and a spring 145 raises the plate 76. The perforations in the plate 76 permit the glue in the glue container 78 to overspread uniformly on the upper 10 surface of the plate.

Operation of invention.

The feeding magazine 20, is filled with loose hairs 32, from a badger or other inexpensive 15 fur-bearing animal. The hairs 32, being in an upright position and pressed lightly in a direction facing the hair picking device 21, by means of the spring 33.

The feeding magazine 20, has a sidewise horizontal step by step reciprocating motion imparted to it automatically by the ratchet wheel 37, and link 38 (see Figs. 3 and 11), so that the hairs 32, are not taken from the magazine 20, continually from one spot. The feeding magazine 20, is also adjustable vertically by means 25 of the foot paddle 39. The vertical adjustment serves to regulate the length to which the hairs 32, shall be cut by the shears 22, and is governed by the length of the hairs on the particular 30 portion of the fur-skin.

A piece of fur-skin 18, to be improved by pointing is laid upon the rotatable drum 11 (see Figs. 1 and 2), and the power shaft 13, is set in motion. The air pipe 17 is connected 35 to an auxiliary air pipe 149, having a nozzle 150, which is disposed in the direction where the pointer rod 24, meets the fur-skin 18. A directed air supply thus impinges upon a fixed point on the fur-skin. The air valve 16, is timed 40 by the cam 14, to open and start blowing on the fur-skin and to spread the hairs apart and to form a cleared spot 19, thereon, thus exposing the fur-skin when the pointing rod 24, starts on its downward movement. The air 45 valve being shut off when the strand of hairs 32, reaches the fur-skin and is glued in position thereon. The fur-skin 18, is shifted by the operator to bring different portions thereof 50 within the influence of the air blast from the nozzle 150, and to glue strands of hair 32, at different portions of the fur-skin as desired.

The loose badger hairs 32 are of light color and have a black portion at one end. As it is desired to glue the hairs with the black ended 55 portion pointing upwardly from the fur-skin, the hairs are placed in the hair magazine 20, with the black ends facing downwardly. As best shown in Figure 13, the hair picking device 21 on its upward swing picked one or more hairs 60 from the hair magazine 20 and the lever 122, contacted with the bar 146 (see Fig. 2) and locked the picking device. The picking device then swings downward to meet the shears 22. The hairs 32 are thus reversed and the dark 65 ended portion faces upwardly. In this position, best shown in Figures 2 and 8, the rod 69, strikes the arm 147, and locks the gripping means 66, thus causing the gripping means to grip the hairs 32; the shears 22 automatically 70 cut the hairs 32 to the proper length as predetermined by the operator. The extension 121, then unlocks the picking device 21. The conveying device 23, carries the hairs in a curved line while the pin 71, moves diagonally along the 75 direction of the slot 72 and then longitudinally

along the slot 73, above the perforated plate 76, thus causing the lower end of the hair to wipe and pick up some of the glue from said plate. The conveying device 23 (see Figs. 3 and 9) then carries the hairs 32 to the pointing rod 24, the lever 148 striking the rod 69 shown in Fig. 8, and causing the hair gripping means 66 to open. In this position the gripping device 77 (see Figs. 2 and 10), on the pointing rod 24 grips the hairs 32 and the pointing rod sets 10 the hair on the cleared spot 19 of the fur-skin 18, where the hairs become glued and fixed in position on the fur-skin 18, with the black ended portion facing upwardly.

An auxiliary air pipe 149, connected to the 15 air pipe 17, is provided to blow the waste hair away from the shears 22 and away from the operator.

Referring to Figures 13, and 14, it is to be noted that the shaft 45, the arm 44, and the 20 picking device 21 have been made hollow, and that an air tube 163, has been attached at the end of the shaft 45, so as to cause a suction to act upon the hairs 32. This suction may be finely regulated so as to pull a definite number 25 of hairs from the hair magazine when the picking device approaches said magazine.

Having thus described my invention, I claim as new and desire to secure by Letters Patent:

1. A fur pointing machine comprising a hair 30 magazine, shears for cutting hairs to length, a hair picking device adapted to pick one or more hairs from said magazine and to place them in operative relationship with said shears, a gluing device, a fur pointing rod, means for conveying 35 the cut hairs from the picking device to the gluing device and then in operative position with the fur pointing rod, means for operating the fur pointing rod to deliver the hair to the fur skin, and air blast means for spreading apart 40 the fur and exposing a cleared portion of said fur skin prior to the approach of the hair to the skin.

2. A fur pointing machine comprising a hair 45 magazine, shears for cutting hairs to length, a hair picking device adapted to pick one or more hairs from said magazine, means for transferring 50 said picked hairs in operative relationship with said shears, a gluing device, a fur pointing rod, means for conveying the cut hairs from the picking device to the gluing device and then in operative position with the fur pointing rod, means for operating the fur pointing rod to receive hair from the conveying device and to deliver the hair to the fur skin, and air blast 55 means for spreading apart the fur for exposing a selected portion of the fur skin prior to the advance of the gummed hair.

3. In a fur pointing machine of the class described, a hair feeding magazine comprising a 60 hair containing member open at the top and adapted for housing hairs in an upright position therein, said hair containing member having an upright opening facing the operating end of the fur pointing machine for withdrawing 65 said upright hairs in a direction transverse of the length of the hair from said containing member, spaced cross members bridging said opening and serving to support said upright hairs, means for automatically imparting a step 70 by step reciprocating motion to said hair feeding magazine, and means for manual adjustment of said hair containing member in a vertical direction.

4. In a fur pointing machine of the class de- 75

scribed, a hair picking device comprising an arm mounted to swing in a vertical plane about a horizontal shaft, a housing integral with said shaft, a bevel gear on said arm adapted to mesh with a bevel gear on said shaft and causing said picking device to rotate, a rack meshing with a gear on said horizontal shaft for imparting said swinging motion to the shaft and to the picking device, said picking device being rotated and swung simultaneously.

5. The invention as defined in claim 4, wherein the effectiveness of said picking device is augmented by air suction means acting through apertures in the said arm and shaft.

10 6. In a fur pointing machine, a hair hopper,

means for removing hair from said hopper, means for longitudinally adjusting the position of the hopper during operation of the machine, and means for trimming the hair removed by said hair removing means to a predetermined length.

7. In a fur pointing machine, a hair hopper, means for adjusting said hopper in a direction longitudinal of the hair therein, means for removing hair from the hopper, means for trimming an end of the hair removed by the removing means, and means for gripping the other end of the hair and for further advancing the hair.

15 NICHOLAS DICKER. 15
